UNITED STATES PATENT OFFICE.

GUSTAV W. ULMER, OF NEWTON, MASSACHUSETTS.

FIRE-ALARM.

SPECIFICATION forming part of Letters Patent No. 248,369, dated October 18, 1881.

Application filed February 14, 1881. (No model.)

To all whom it may concern:

Be it known that I, GUSTAV W. ULMER, of Newton, in the county of Middlesex and State of Massachusetts, have invented certain Improvements in Fire-Alarm Signaling Apparatus, of which the following is a specification.

This invention relates to pneumatic fire-alarm signaling apparatus; and the invention has for its object to adapt a horn or trumpet adapted to be operated by compressed air, similar to those now in use for fog alarms or signals, to the purpose of a fire-alarm; and the invention consists, as a whole, in the combination of a horn or trumpet adapted to be operated by a blast of air, and provided with a self-closing valve to control the admission of air thereto, mechanism for supplying compressed air to the trumpet, and a let-off mechanism capable of being controlled from a distance to open the valve of the trumpet.

The invention also has for its object to provide certain improvements in a hydraulic motor for operating the air-compressing mechanism, whereby the operation of said mechanism, which is suspended when the column of air between the compressing mechanism and the trumpet is compressed to the necessary degree, is enabled to be immediately resumed when the compression of said column is relieved by the escape of a portion of the air to operate the trumpet; and to this end the invention consists in the combination, with a horn or trumpet having a self-closing valve, mechanism controlled from a distance to open the valve, and an air-compressor to force air to the trumpet, of a primary hydraulic motor for operating the compressor and a secondary hydraulic motor, whereby the prompt and positive action of the slide-valve of the primary motor is secured and one of the supply-ports of said valve kept constantly open, so that the prime motor is ready for immediate operation whenever the pressure of the column of air between the compressor and the trumpet is relieved.

In carrying out my invention I make use of the apparatus and mechanism which I will now proceed to specifically describe and claim, reference being had to the accompanying drawings, forming part of this specification, in which—

Figure 1 represents a side view of apparatus embodying my invention. Fig. 2 represents a section on line $z z$, Fig. 1, looking toward the hydraulic cylinder. Fig. 3 represents a vertical section through the valve-chest of said cylinder. Fig. 4 represents a transverse section through the valve-chest of the secondary hydraulic motor, exhibiting also a side elevation of the cylinder of said motor. Fig. 5 represents a section on line $x x$, Fig. 4. Fig. 6 represents an elevation of the valve of said motor. Fig. 7 represents a section on line $y y$, Fig. 6; Fig. 8, a similar section on line $y' y'$; Fig. 6. Figs. 9 and 10 represent elevations of the same valve turned to the right and left, respectively. Fig. 11 represents a perspective view of the electrical mechanism for operating the valve of the trumpet. Fig. 12 represents a vertical section, enlarged, of the base of the trumpet, showing the trumpet-valve.

In all the foregoing figures the same letters refer to the same parts.

In the drawings, T is a horn or trumpet similar to those in use in the ordinary fog alarm apparatus, connected with a compressed-air reservoir, R, interposed between the horn and the cylinder B of an air-compressor, adapted to supply the reservoir R with compressed air through the pipe y entering each end of the cylinder B, and provided with valves v v'.

P is a piston-rod common to the cylinder B and to the cylinder A of a hydraulic motor, and having proper pistons at each end working in said cylinders. The water-cylinder A is supplied with water through the pipe a', connected with the cylinder by the ports p p', b' being the exhaust-pipe of said cylinder and C the valve-chest, an ordinary D slide-valve being used. In operation the water enters each end of the cylinder A alternately as steam enters the cylinder of an ordinary horizontal engine, thus effecting the movement of the piston-rod P and a corresponding movement of the piston of the air-cylinder B, attached to said piston-rod, the apparatus acting as a primary hydraulic motor to force air from the cylinder B and compress the same within the reservoir R. In the drawings the piston-rod P is moving to the left, as indicated by the arrow, Fig. 1, the water entering the end h² of the cylinder A and exhausting from the end h'.

Water under pressure, unlike steam, possesses no elasticity, and as it is necessary for the effective operation of the apparatus embodied in my invention that the exhaust and supply ports of the cylinder A be opened quickly, I operate the slide-valve *d* by means of a secondary hydraulic motor or cut-off device consisting of a cylinder, D, connected to the chest C and having a piston, *i*, connected with the slide-valve *d* by the valve-rod *r*.

Projecting from one side of the cylinder D is a valve-chest, D', having on its face supply-ports 1 and 2 and an exhaust-port, 3. The port 1 is connected with one end of the cylinder D by a passage, *a*, and the port 2 with the other end of said cylinder by a passage, *b*. The exhaust-port 3 is connected with the exhaust-pipe *b'* of the cylinder A by means of the waste-pipe *b*². Water is supplied to the cylinder D by the pipe *a*³, the valve-chest D' being always full of water.

V is a pivoted valve, adapted to be rotated to right and left alternately by means of a crank, *l*, at the outer extremity of the chest D'.

Attached to the crank *l* is a rod, *e*, having adjustable dogs *f f'* at each end, respectively.

The piston-rod P has rigidly attached to it, midway between the cylinders A and B, a double-arm lever, L. The lower arm of the lever L slides upon a horizontal guide-rod, *m*, acting to steady the lever and prevent it from turning. The upper arm slides upon the rod *e*, whose dogs *f f'* are so adjusted that when the piston-rod and arm of the lever L are nearing the end of a stroke the arm of the lever will strike a dog and carry the rod *e* with it, and thus swing the lever *l* and rotate the valve V.

The valve V has upon its face three ports near its periphery, 1', 2', and 3', the central port, 3', being connected by a passage, K, with the center of the valve 4. The face of the valve V is so adjusted in relation to its seat in the chest D' that when port 1' of the valve is opposite port 1 of the seat the exhaust-port 3' of the valve will be opposite port 2 of the seat, so that a supply of water will pass from the chest D' through port 1' of valve and port 1 of seat into one end of the cylinder D, and exhaust-water from the other end of said cylinder will pass through port 2 of the seat and port 3' of the valve. The operation is exactly similar, except reversed, when the port 2' of valve is opposite port 2 of seat. The central opening, 4, of the valve being always coincident with the opening 3 of the valve-seat, it will be seen that at either end of the stroke of the piston *i* the exhaust-water passes through port 3' and opening 4 of the valve and opening 3 of the valve-seat, down the passage *c'* (see Fig. 5) into the waste-pipe *b*² and exhaust-pipe *b'*.

By the operation of the valve V, as described, movement of the piston *i* is secured for operating the slide-valve *d*. This mode of operating the valve *d* by means of a secondary motor differs essentially from an eccentric-valve motion, whereby the valve *d* moves constantly with the

piston P. By my improvement, as described, the valve *d* is independent of the main cylinder A and its piston, in so far as the piston P does not directly connect to or move it. Although the primary impulse or force is derived from said piston P, the cut-off afterward is made independently and in independent time. This mode of operating the main slide-valve of hydraulic motors is an important and valuable improvement over any valve motion with which I am acquainted, and its application to the apparatus embodying my invention secures the prompt action of the valve *d* and renders it possible to keep one of the supply-ports *p p'* of the cylinder A constantly open, for the purpose hereinafter set forth.

E is a pipe, (in connection with the supply-pipe in this case,) containing a device for maintaining the valve *d* in equilibrium, said device consisting of a lever, *n*, connected to the valve *d* by a pin acting in an adjusting-slot, *s'*, so as to enable the lever *n* to swing freely. The opposite end of the lever *n* is jointed to the rod *o*, having upon it the piston *t*. The rod *o* has a bearing in the perforated plate *o'* and in the upper end, *o*², of the pipe E. C' is an air-chamber, all the foregoing parts being so adjusted that when the valve *d* moves, the lever *n*, connected with the piston *o*, imparts movement to the piston *t*, and so tends to compress the air within the chamber C', this pressure reacting on the valve *d*, and so maintaining it in equilibrium.

The valve of the trumpet T may be operated by any suitable mechanism adapted to be controlled from a distant point. In Fig. 11 I have shown an electrical escapement for operating said valve. In said figure, M is an electro-magnet connected in a battery or magneto circuit, *a*⁴ being the armature of said magnet, secured to the vibrating lever *a*⁵. F F is a frame, on which are mounted shafts *h k q q'*. *h*, *k*, and *q* are connected by gears, as shown, the shaft *q* bearing a drum which sustains a weight, W, said weight, when unobstructed, operating to rotate the shafts *q*, *k*, and *h*. On the shaft *h* is a disk, *h*³, having projecting from its face a pin or block, *c*. Upon the shaft *q'* is a triple-arm lever, *c' d' e'*, capable of rotating on said shaft. The arm *c'* normally rests in a notch, *t'*, in the lever *a*⁵. The arm *d'* rests normally against the pin *c* of the disk *h*³ and prevents the shafts *h k q* from rotating. The arm *e'* reaches under a cam, 5, on the shaft *k*. At the opposite end of the shaft *q'*, and free to rotate upon it, is a double-arm lever, 7 8. The arm 8, projecting upwardly, is drawn to a normal position by a spring, *s*, so that the lower arm, 7, will rest in the hollow of the cam 6 on the shaft *k*.

The mechanism operates as follows: A pulsation or momentary current of electricity being sent through the circuit by pressing a key or otherwise, the armature and lever *a*⁴ *a*⁵ are drawn to the magnet M, releasing arm *c'*, which is thereupon drawn downwardly by a spring, *s'*, thus throwing up the arm *d'* and permitting the disk *h*³ and shaft *h* to be rotated by the

- weight W. The current being momentary, the armature and lever immediately drop away from the magnet, and the arm e' is thrown up and locks into its notch t' by means of the cam 5 on the shaft k, rotating in such time as to throw down the arm e', and thus cause the arm d' to catch the pin c and stop the rotation of the disk h³. During the time the shafts h k q are rotating the cam 6, also rotating, throws 10 down the arm 7 of the double lever, thus throwing forward arm 8. A wire or cord, 9, connects the arm 8 with the lever g, attached to the valve v² of the trumpet, and so opens the said valve and allows a blast to be sounded on the trumpet. When the electrical mechanism just described returns to its normal position the valve v² is closed.
- I do not confine myself to an electrical escapement just described, as any form of escapement or any mechanism capable of being controlled from a distant point is equally applicable for the purpose of my invention.
- The valve v² operates as follows: The lever g is attached to a shaft, g', having thereon a cam, g³. When the lever is lifted the cam is rotated and acts to depress and so open the valve, at the same time compressing the spring s³. When the pressure of the cam is removed the valve is closed by the spring s³ returning 30 to its normal position. Within the trumpet T I place a reed or reeds, R', for the purpose of regulating the tone of the blast sounded on the trumpet. When more than one reed are employed a composite tone may be given to said blasts.
- The operation of my invention as a whole is as follows: Water being introduced into the cylinders A and D through the supply-pipes a' a³, the piston P of the prime motor is made 40 to force air from the cylinder B and compress the same within the reservoir R in sufficient amount and pressure to operate the trumpet. The piston P is then brought to rest. By the action of the secondary motor D regulating the valve d, as previously described, the prompt operation of said valve is secured, and when the piston P is brought to rest one of the supply-ports of the cylinder A is left open. When it is required to give an alarm the trumpet is 50 blown, air being admitted thereto from the reservoir R through the valve v², operated by means of the electrical mechanism previously described. The pressure of the column of air between the reservoir R and the air-compressing cylinder B being relieved by the escape of air through the valve v² in blowing the trumpet, the piston P immediately begins to operate, the primary motor being ready for instant action, and sufficient compressed air is forced 55 into the reservoir R to carry the pressure of the air in said reservoir back to the point at which it was held previous to giving the alarm, when the piston P is again brought to rest, and thus the apparatus is made ready for sounding another alarm.
- The advantages of my invention for fire-alarm purposes will be apparent, inasmuch as the apparatus is constantly ready for operation, and after a blast or series of blasts upon the trumpet the apparatus returns automatically to an operative condition.
- My invention is applicable for use in a fire-alarm-signal circuit for towns and cities in place of bells, or wherever it is inexpedient or inconvenient to use bells.
- I do not restrict myself to the above-described method of compressing air by mechanical means, as it would be equally applicable to the purpose of my invention to compress air by a chemical process analogous to that employed in the ordinary chemical fire-extinguishing apparatus, wherein certain chemical constituents are prepared, ready for mixing at any desired moment, and when so mixed expand, and thus may be made to compress air within the reservoir R in sufficient volume to produce blasts upon the trumpet.
- Having thus described my invention, what I claim, and desire to secure by Letters Patent, is—
1. In a fire-alarm, the combination of a horn or trumpet adapted to be operated by a blast of air and provided with a self-closing valve to control the admission of air thereto, mechanism, substantially as described, for supplying compressed air to the trumpet, and a let-off mechanism, substantially such as described, and capable of being controlled from a distant point to open the valve of the trumpet, as set forth.
2. In a fire alarm, the combination of the following elements, viz: first, a horn or trumpet having a self-closing valve; secondly, mechanism, substantially such as described, capable of being controlled from a distance to open the valve; thirdly, an air-compressor adapted to force air to the trumpet; fourthly, a primary hydraulic motor for operating the compressor, said motor being composed of a cylinder having ports p p', a piston having a rod, P, connected with the compressor, and a slide-valve, d, to regulate the passage of water to the cylinder through the ports p p'; and, fifthly, a secondary hydraulic motor having its piston connected with the slide-valve d and its valve V adapted to be operated by attachments of the piston-rod P to shift the slide-valve d before the completion of each stroke of the piston of the primary motor, whereby the prompt and positive operation of the slide-valve d is secured and one of the ports p p' is always kept open, so that the primary motor is ready for operation whenever the air between the compressor and the trumpet is decreased by the escape of such air to operate the trumpet, as set forth.
- In testimony whereof I have signed my name to this specification, in the presence of two subscribing witnesses, this 7th day of February, A. D. 1881.

GUSTAV W. ULMER.
